LOCKING CLOSURE FOR CONTAINERS

Jack W. Soffer, St. Louis, Mo., assignor to Development Research, Inc., St. Louis, Mo., a corporation of Missouri

Application December 8, 1951, Serial No. 17,650

Term of patent 14 years

(Cl. D58—26)

To all whom it may concern:

Be it known that I, Jack W. Soffer, a citizen of the United States, residing at the city of St. Louis, State of Missouri, have invented a new, original, and ornamental Design for a Locking Closure for Containers, of which the following is a specification, reference being made to the accompanying drawing, forming a part thereof, in which:

Figure 1 is a perspective view taken from above of a locking closure for containers embodying my new design;

Figure 2 is a perspective view showing said locking closure inverted;

Figure 3 is a plan view thereof; and

Figure 4 is a side elevational view thereof.

I claim:

The ornamental design for a locking closure for containers, substantially as shown.

JACK W. SOFFER.
